UNITED STATES PATENT OFFICE

119,518

DESIGN FOR A PIANO

William Zaiser, Rockville Centre, N. Y., assignor
to The Rudolph Wurlitzer Company, Cincinnati, Ohio, a corporation

Application July 8, 1939, Serial No. 85,921

Term of patent 7 years

To all whom it may concern:

Be it known that I, William Zaiser, a citizen of the United States, residing at Rockville Centre,
in the county of Nassau and State of New York,
have invented a new, original, and ornamental Design for a Piano, of which the following is a specification, reference being had to the accompanying drawing forming part thereof.

In the drawing:

Fig. 1 is a perspective view of a piano, showing my new design; and Fig. 2 is a front elevational view thereof on an enlarged scale.

I claim:

The ornamental design for a piano, as shown.

WILLIAM ZAISER.
